UNITED STATES PATENT OFFICE.

RAYMOND C. ROCHELLE, OF HUBBARD, TEXAS.

TYPE-WRITER COVER.

1,139,804.

Specification of Letters Patent. Patented May 18, 1915.

Application filed February 3, 1914. Serial No. 816,271.

To all whom it may concern:

Be it known that I, RAYMOND CASPER ROCHELLE, citizen of the United States; residing at Hubbard, in the county of Hill and State of Texas, have invented certain new and useful Improvements in Type-Writer Covers, of which the following is a specification.

My invention relates to new and useful improvements in collapsible cases or covers for typewriters, being more particularly an improvement over the form of cover disclosed in my copending application filed September 3, 1913 and bearing the serial

15 No. 787,911, the primary object of my invention being the provision of a cover which may be more cheaply constructed and which, at the same time, will be more efficient and satisfactory in use.

20 A further object of my invention is the provision of a typewriter cover including a base adapted to receive the typewriter and a flexible hood or cover proper detachably connected to the base and extensible over the

25 typewriter.

A still further object of my invention is the provision of a simple supporting frame for the hood including a plurality of bows detachably connected to the base and carrying the hood, the base being provided with integrally formed stops for limiting the swinging movement of the bows when they are swung rearwardly to expose the typewriter.

30 A still further object of my invention consists in a novel means for securing a strip or pad of felt or other soft material to the base to prevent injury to desks, tables or other articles of furniture upon which the

40 typewriter may be placed.

With these and other objects in view, my invention will be more fully described, illustrated in the accompanying drawings and then specifically pointed out in the claims

45 which are attached to and form a part of this application.

In the drawings:—Figure 1 is a longitudinal sectional view taken through my improved typewriter cover, a conventional typewriter being shown in place; Fig. 2 is a fragmentary view similar to that shown in Fig. 1 but showing the cover supporting bows swung to rearward or open position and the rear lower edge of the cover disconnected from the base; Fig. 3 is a fragmentary perspective view of my improved type-

writer cover, the hood or cover proper being shown in dotted lines, while the base and frame work are shown in full lines; Fig. 4 is a fragmentary top plan view, illustrating the manner of mounting the bows upon the base and the operation of the stop for limiting their rearward and downward swinging movement; Fig. 5 is a plan view of the stamped out blank from which the metal base is formed, a portion of the blank being broken away to permit its showing upon an enlarged scale; Fig. 6 is a fragmentary sectional view, showing a modified form of key-hole slot and bow construction; Fig. 7 is a fragmentary perspective view of the bow illustrated in Fig. 6; Fig. 8 is a similar view of a further modified form of bow; Fig. 9 is a fragmentary sectional view, showing a different method of attaching the cover to the base.

In order to insure a clear and full understanding of my invention and the manner of its use, I have illustrated my improved typewriter cover in connection with a conventional typewriter 10 having a plurality of supporting feet 11. The typewriter cover includes primarily a base 12, a plurality of bows 13 swingingly connected to the base and a fabric hood or covering 14 secured to the bows and detachably connected at one edge to the rear edge of the base.

More specifically, the base is formed from a sheet metal blank struck-out in a single piece in the shape best shown in Fig. 5, the blank being substantially rectangular in shape with laterally directed wings 15 extending from its sides at its rear edge and laterally directed tongues 16 extending from its sides at its forward edge. Preferably, the forward edge portion is cut-away centrally as shown at 17 to lighten the construction.

In forming the base from the above described blank, the rear portion of the blank, namely that portion extending between the wings 15, is bent upwardly at right angles to the body of the blank to form a flange or back wall 18, after which the wings 15 are swung inwardly to bear at their lower edges upon the upper face of the body of the blank when their reduced terminals 19 are bent outwardly at right angles to form stops to receive the swinging bows 13, as will be later more fully explained. The tongues 16 are then bent up at right angles to the body portion in the manner best shown in Fig. 3.

Preferably, the base 12 is upstruck marginally along its side and rear edges to provide a substantially U-shaped seat 20 to receive a strip 21 of heavy felt or other suitable material serving as a cushion to prevent injury to any finished surface upon which the device may be placed.

In order to provide means for attaching the bows and cover 14 to the base so constructed, the flange or rear wall 18 is perforated at spaced intervals to receive the head members 22 of snap fastening devices 23, the socket members 24 of said devices being stitched or otherwise secured to the rear lower edge of the covering 14, as will be later explained. The tongues 16 are each provided with a plurality of vertically disposed key-hole slots 25 spaced one in advance of the other with their larger ends 26 uppermost. It will of course be understood that these slots and the perforations for the snap fastening members 20 are stamped out during the initial forming of the blank and before the parts are bent into the position described and illustrated in Fig. 3.

Each tongue 16 is provided with one key-hole slot for each frame member or bow 13, there preferably being three of these bows in order to properly spread and hold the cover in position. Each of these bows is preferably formed from a single piece of wire either circular or angular in cross section with their free ends bent inwardly as shown at 26 and headed to provide ball terminals 27 proportioned to pass through the larger ends of the key-hole slots and to retain the indent terminals 26 of the bows against disengagement from the slots when the bows are lowered to let such portions rest upon the lower edges of the slots. By this means, it will be clear that the bows may be readily attached to or detached from the base and at the same time will not be liable to become casually disengaged. Preferably, the bows vary slightly in width in order that upon swinging of the frame into rearward or open position, they may all engage and rest upon the stops 19. Because of this construction, the bows will not strike upon the table, desk or other article of furniture upon which the device is employed when swung to open position.

The cover proper 14 is preferably formed of fabric, although it may be made of leather, rubber or any other suitable and flexible material. This cover, as previously explained, is provided at its rear lower edge with the socket members 24 of the snap fastening devices 23 in order that it may be detachably secured to the rear wall 18 of the base and is preferably cut-away slightly at either side as shown at 28 to engage snugly about the stops 19. It is so proportioned that when secured to the bows, by stitching or other suitable means, as shown in Fig. 1

of the drawings, the swinging of the bows and cover to closed position, as there shown, will stretch the cover in such a manner as to completely inclose the typewriter without resting against any part of it. The sides of the two rearmost bows are preferably substantially equal in length, while the sides of the forward bow are considerably longer. These side portions of the forward bow, adjacent the intermediate portion, are preferably provided with studs 29 of rubber or other suitable cushioning material proportioned to engage against the upper face of the supporting desk or table when the cover is in closed position to prevent any possible marring of the surface of the furniture by the bow. At this point it should be noted that the weight of the bows and cover tend, at all times, to hold the ball terminals of the bows in the lower ends of their slots and therefore to prevent disengagement of the frame and cover from the base, this being true whether the cover is in open or closed position. It should further be noted that, inasmuch as all of the bows are swingingly connected to the base, the cover, when in rearward or open position, is located entirely at the rear of the typewriter and therefore cannot in any way interfere with the movement of the typewriter carriage or other parts of the machine, the typewriter being positioned with its rearmost feet 11 upon the base 12 and therefore holding the base and its cover against movement. It will of course be understood that, if desired, the base 12 may be made to extend forwardly the entire extent of the typewriter to completely support the latter. This, however, is a more expensive construction and usually not desirable.

The above described cover may be readily and economically manufactured as the base may be stamped out in a single operation. This base is preferably formed of comparatively light sheet metal and the entire cover may therefore be readily shipped through the mails. The ready packing and shipment of these covers is greatly facilitated because of the fact that the cover proper, together with its bows, may be detached from the base and the device as a whole more compactly packaged.

For instance, although key-hole slots may be employed, I preferably provide the tongues 16 with key-hole slots of the type shown in Fig. 6 in which the lower end is somewhat enlarged as shown at 30. The larger upper ends of these slots are equal in size to the ball terminals of the bows 13 and the slightly enlarged lower ends 30 to the diameter of the bows 13. The laterally directed portions 26 of the bows are reduced in thickness in the plane of the bodies of the bows in such a manner as to pass freely through the body portion of the slots when

the bows are in vertical position but to prevent such movement when the bows are swung to any other position. This absolutely locks the bows against movement to the upper ends of the slots when the cover is in open position.

If preferred, the key-hole slots may be entirely done away with and the tongues 16 merely perforated to receive the ends of bows having a reduced terminal 31 as shown in Fig. 8, this terminal being perforated to receive a cotter pin 32 by means of which the bow is locked in place.

Instead of employing the snap fasteners for securing the cover to the upturned flange of the base, rivets 33 may be employed, being passed through the fabric of the cover and through the perforations in the flange, as clearly shown in Fig. 9.

Although I have illustrated and described my invention in all its details of construction, it will of course be understood that I do not wish, in any way, to be limited by such details, as various minor changes, whether in the scope of the appended claims, may be made without in the slightest degree departing from the spirit of my invention.

Having thus described the invention, what is claimed as new is:

1. A cover for typewriters including a base provided at its sides with upturned

tongues having key-hole slots, a plurality of bows having inturned balled terminals engageable in the slots, and a fabric covering mounted on the bows and secured at its rear edge to the rear edge of the base.

2. A cover for typewriters including a sheet metal base upstruck to provide a marginal channel in its lower face, a packing strip seated in the channel and extending below the lower face of the base, and a cover carried by the base.

3. A cover for typewriters including a base formed from a single blank of sheet metal bent to provide an upturned rear wall having forwardly directed wings with laterally directed terminals forming rests and also upturned to provide at the sides tongues having key-hole slots, a plurality of bows having inwardly directed balled terminals engageable in the slots of the tongues, said bows being adapted to swing into engagement with the rests, and a fabric covering carried by the bows and detachably connected to the rear wall of the base.

In testimony whereof I affix my signature in presence of two witnesses.

RAYMOND C. ROCHELLE.
